UNITED STATES PATENT OFFICE.

JOSEPH D. PUTERBAUGH, OF FREMONT, OHIO.

SIGNAL.

Application filed August 28, 1922. Serial No. 583,882.

To all whom it may concern:

Be it known that I, JOSEPH D. PUTERBAUGH, a citizen of the United States, residing at Fremont, in the county of Sandusky 5 and State of Ohio, have invented new and useful Improvements in Signals, of which the following is a specification.

This invention relates to a railroad signal, the general object of the invention being to 10 provide a vertically movable member which is raised when the train approaches a crossing and is held in raised position until the train passes the crossing when a part actuated by the train releases the member and 15 permits it to drop.

Another object of the invention is to provide means for lighting a lamp when the member is in raised position.

This invention also consists in certain 20 other features of construction and in the combination and arrangement of the several parts, to be hereinafter fully described, illustrated in the accompanying drawings and 25 specifically pointed out in the appended claims.

In describing my invention in detail, reference will be had to the accompanying drawings wherein like characters denote like or corresponding parts throughout the several views, and in which:—

Figure 1 is a plan view of a railroad crossing showing my invention in use.

Figure 2 is an elevation of the parts shown in Figure 1.

Figure 3 is a longitudinal sectional view 30 through the device.

Figure 4 is a plan view of the device.

Figure 5 is a fragmentary sectional view showing the device in raised position.

Figure 6 is a detail sectional view showing 40 how the cables pass into the housing from the pulleys.

Figure 7 is a diagrammatic view of the circuits.

In these views A indicates the track and 45 B the crossing. The signal means consists of a housing 1 placed adjacent the crossing and in which is movably mounted a column 2. This column is adapted to be raised by

means of the motor 3, said motor actuating 50 the drum 4 to which is connected the cables 5 which are fastened to guides 6 at the lower end of the column. The cables pass over suitable guiding pulleys 7. The guides

6 engage the rods 7' which are arranged 55 within the housing. A coil spring 8 in the

bottom of the housing engages the bottom of the column when the same is in lowered position. An electric lamp 9 is mounted on the top of the column and a cover 10 is placed 60 over the lamp, said cover being supported by the posts 11 which are connected with the top of the column. The cover 10 will rest on the top of the housing when the column is in lowered position so that no light will 65 be seen when the parts are in this position. Contacts 13 are connected with the top of the housing and these contacts are connected by the conductors 14 with a source of supply. Conductors 15 are carried by the column 70 and these contacts are connected by the conductors 16 with the lamp. These parts are so arranged that when the column is in raised position the contacts 15 will engage the contacts 13 and thus complete the circuit to the lamp. The motor circuit is provided with a switch 17 which is adapted to be opened, by a projection 18 on the column when the column is in raised position. The column is held in raised position by a latch 75 19 and this latch has a part arranged adjacent one of the rails so that it will be engaged by the wheels of a train so as to move the latch to releasing position and thus permit the column to drop. A spring 20 holds 80 the latch in engaging position.

As the train approaches the crossing it will close the circuit to the motor so that the motor will begin to actuate and thus raise 85 the column. The motor will continue to 90 operate until its circuit is broken by the projection 18 striking the switch 17. By this time the latch 19 has come into engagement 95 with the bottom of the column so that said latch will hold the column in raised position. The lamp is now lighted due to the closing 100 of its circuit by the contacts 15 engaging the contacts 13. The parts will remain in this position until the train passes the crossing when the wheels of the train will operate the latch to cause it to release the column 105 and thus the column will drop upon the spring 8 which acts to absorb the shock of the dropping column. This invention will give a warning that the train is approaching the crossing both by the light and the rising column.

It is thought from the foregoing description that the advantages and novel features of my invention will be readily apparent.

I desire it to be understood that I may 110 make changes in the construction and in the

combination and arrangement of the several parts, provided that such changes fall within the scope of the appended claims.

What I claim is:—

- 5 1. A signal of the class described comprising a housing, a vertically movable member therein, a motor for raising the member, means for closing the circuit to the motor by a train approaching the crossing, means 10 for breaking the circuit of the motor when the member reaches a certain position, a latch for holding the member in raised position and means actuated by the train for disengaging the latch after the train passes 15 the crossing.
2. A device of the class described comprising a housing, a vertically movable column therein, a motor for raising the column, means for closing the circuit to the motor by 20 a train approaching the crossing, means for breaking the circuit to the motor when the column reaches a certain position, latch

means for holding the column in raised position, means for releasing the latch means by the train after it passes the crossing, a 25 lamp on the column, and means for lighting the same when the column reaches its raised position.

3. A device of the class described comprising a housing, a vertically movable column therein, a motor for raising the column, means for closing the circuit to the motor by a train approaching the crossing, means for breaking the circuit to the motor when the column reaches a certain position, latch 35 means for holding the column in raised position, means for releasing the latch means by the train after it passes the crossing, a lamp on the column, means for lighting the same when the column reaches its raised position 40 and means for enclosing the lamp when the column is in lowered position.

In testimony whereof I affix my signature.

JOSEPH D. PUTERBAUGH.
